UNITED STATES PATENT OFFICE.

CLARENCE L. DALTON, OF CINCINNATI, OHIO, ASSIGNOR TO CHARLES H. ALBRECHT, OF SAME PLACE.

WHIP-HOLDER.

SPECIFICATION forming part of Letters Patent No. 349,341, dated September 21, 1886.

Application filed December 16, 1885. Serial No. 185,802. (No model.)

To all whom it may concern:

Be it known that I, CLARENCE L. DALTON, a citizen of the United States, and a resident of Cincinnati, Hamilton county, Ohio, have 5 invented certain new and useful Improvements in Whip-Holders, of which the following is a specification.

The several features of my invention and the various advantages resulting from their 10 use, conjointly or otherwise, will be fully hereinafter set forth.

In the accompanying drawings, Figure 1 is a perspective view of my improved whip-socket attached to the vertical bar of a dash-frame. Fig. 2 is a perspective view showing the socket as made from a single piece of wire. Fig. 3 is a perspective of the socket as made 15 from two pieces of wire. Figs. 4 and 5 show a pair of clamps for holding the wire frame of 20 the socket.

The wire A is bent to the shape shown in Fig. 3, forming the vertical wires a' a^2 a^3 a^4 and loops a^5 a^6 . By reference to the drawings, it will be seen that this shape is such as to 25 produce a socket with two springs, each pressing inwardly. The first spring is at the upper part of the socket, and is formed by the wires a' a^2 in the front, tending to press toward the wires a^3 and a^4 in the rear. The second spring 30 is located below and is formed by the wires a' and a^4 on one side pressing toward the wires a^2 and a^3 on the other. Thus these two compression-springs act at right angles to each other. The wire B is bent into a circular 35 form, and its ends turned up to form the projections b b . The modification shown in Fig. 2, in which the whole socket is formed from a single wire, is readily understood from the drawings.

40 The clamp for holding the socket to the dash-frame is shown in Figs. 1, 4, and 5. The anterior plate, D, of the clamp is provided with two longitudinal grooves, d d . Projecting from the sides of the plate are two lugs, d' . 45 The rear plate, E, is provided with two grooves, e e , corresponding to the grooves d d of the plate D. When the two plates D and E are brought together, the grooves d d fit over the grooves e e . Two or more pins or orifices may 50 be used for riveting or fastening the plates

together. That side of the plate E which is not shown in Fig. 4 is shaped to conform to the outline of the bar of the dash-frame, as shown in Fig. 1. The blanks intervening between the grooves are cut away in the center, forming central depressions, e^2 and d^2 , which are continuous with their respective grooves e and d . 55

The device is put together, as shown in Fig. 1. The ends a^5 and a^6 of the wire A and the ends b b of the wire B rest in the channels formed by the grooves e and d . It is then placed in position with reference to the bar of the dash-frame, and the screws G slipped through the ends of the brace F and screwed into the lugs d' . When the screws G are tightened, the plates D and E are clamped together, firmly holding the wire frame between them, and at the same time the socket as a whole is clamped in position on the bar of the dash-frame. In 70 the use of these plates D and E the ends a^5 and a^6 are curved round toward each other, so as to fit into the space e^2 d^2 , and the ends b b are similarly turned toward each other to fit into the same space. Now, when the socket is 75 clamped together, the wires cannot possibly be pulled out.

When the whip-handle is forced into the socket, it is tightly held by the double spring already described. At the bottom of the 80 socket the whip-handle rests on the two loops formed by the wires a' and a^4 and a^2 and a^3 . The loop B' prevents the socket being pulled apart. It may be omitted, or several loops B may be employed. 85

The advantages of this socket are its reliability and its cheapness.

Among the various advantages of my invention which can be mentioned are the following, viz: The holder automatically adjusts 90 itself to any sized whip. The holder possesses great strength and durability. It is light of weight and cheap of manufacture. Another prominent feature of advantage consists in the fact that it is always very reliable, and does 95 not get out of order.

While the various features of my invention are preferably employed together, one or more of said features may be used without the remainder, and in so far as applicable one or 100

more of said features may be used in connection with whip-sockets other than the one herein specifically described.

What I claim as new and of my invention, and desire to secure by Letters Patent, is—

1. A wire whip-holder having four upright wires curved to form a double spring, substantially as and for the purposes specified.

2. The combination of the wire whip-socket to A and the inclosing-guard, substantially as and for the purposes specified.

3. The combination of the wire whip-socket having wires a^3 and a^4 and clasping-plates having depressions to receive said wires, substantially as and for the purposes specified.

4. The combination of the wire whip-socket having wires a^3 and a^4 and plates E D, having

grooves, and the spaces e^2 d^3 , substantially as and for the purposes specified.

5. The combination of the wires A and B and the clasping-plates provided with grooves, substantially as and for the purposes specified.

6. The combination of the wires A and B, the clasping-plates provided with grooves, and spaces e^2 d^3 , substantially as and for the purposes specified.

7. The combination of the wires A and B, the clasping-plates provided with grooves, and the clasping-brace F, substantially as and for the purposes specified.

CLARENCE L. DALTON.
